United States Patent Office

Des. 185,783
Patented Aug. 4, 1959

185,783

NECKTIE

Samuel Klaus, Brooklyn, N.Y.

Application January 22, 1957, Serial No. 44,534

Term of patent 7 years

(Cl. D3—16)

FIG. 1

FIG. 2

FIG. 3

FIG. 4.

Fig. 1 is a fragmentary front elevational view of the wide end of a necktie showing my new design;

Fig. 2 is a side elevational view thereof;

Fig. 3 is a rear elevational view thereof; and

Fig. 4 is a front elevational view, on reduced scale, of the entire necktie.

I claim:

The ornamental design for a necktie, as shown.
